(57) **CLAIM**

The ornamental design of a slidable and rotatable coupler for a prosthetic leg, as shown and described.

DESCRIPTION

FIG. 1 is a perspective view of a slidable and rotatable coupler for a prosthetic leg, showing our new design;

FIG. 2 is a top view thereof;

FIG. 3 is a bottom view thereof;

FIG. 4 is one side view thereof; and,

FIG. 5 is another side view thereof.
